UNITED STATES PATENT OFFICE.

PETER J. MUENCHEN, OF NEW YORK, N. Y., ASSIGNOR TO ARCTIC REFRIGERATION MANUFACTURING CORPORATION, OF WILMINGTON, DELAWARE, A CORPORATION OF DELAWARE.

REFRIGERATING SYSTEM.

Application filed October 31, 1925, Serial No. 65,931. Renewed January 16, 1929.

My invention relates to refrigeration, and the object is to provide an inexpensive, efficient, reliable and automatic system and apparatus for producing cold by means of a liquefied gas such as carbon dioxide, which when expanded in a suitable chamber or vessel produces intense cold with formation of snow consisting of frozen refrigerant. With these ends in view, the invention may 10 be said to consist in the parts, improvements and combinations hereinafter and more particularly set forth in the appended claims.

In the drawings forming part hereof:

Fig. 1 is an elevation, partly schematic, of 15 a form of the invention suitable for domestic refrigerators:

Fig. 2 is a horizontal section on the line 2—2 of Fig. 3, through the refrigerating unit seen in Fig. 1.

Fig. 3 is a vertical section taken on the line 3—3 of Fig. 2 through this refrigerating unit, a portion of which is seen in elevation;

Fig. 4 is a view, partly in elevation and partly in vertical section, of the expansion 25 chamber or snow vessel;

Fig. 5 is a vertical section through a short tubular casing corresponding to the upper part of Fig. 4;

Fig. 6 is a bottom plan of Fig. 5;

Fig. 7 is an axial section on a larger scale through a multiple nozzle seen in Figs. 5 and 6;

Fig. 8 is a perspective view of a nozzle disc;

Fig. 9 is a vertical section through a regulator;

Fig. 10 is a vertical section through another regulator.

Fig. 11 is a horizontal section on the line 11—11 of Fig. 9;

Fig. 12 is a vertical section through another form of expansion chamber showing the remainder of the apparatus in elevation;

Fig. 13 is a perspective view of one of the discs or plates seen in Fig. 12;

Fig. 14 is a schematic view, principally in elevation, with portions in section illustrating a system for chilling air to be circulated through a building; and

Fig. 15 is a schematic view illustrating another form of the invention, in which the expansion chambers are in the form of radiators.

Figs. 1—11 will first be described.

The part marked 2 represents a flask of liquefied carbon dioxide, from the outlet of which the refrigerant may pass through a flexible copper conduit 3, 3^a to a nozzle body 4. The conduit section 3^a is a continuation of the conduit 3, the passageway at the point between these sections being automatically controlled by a regulator 5, in a manner which will be described hereinafter.

The nozzle body 4 has a screw-thread 6 enabling it to be screwed tightly into one end of a cylindrical vessel 7, the interior of which constitutes an expansion chamber which becomes filled with intensely cold carbon dioxide snow or ice as the result of the expansion and evaporation of the refrigerant admitted through the fine nozzle orifices.

The part 7, instead of being a complete cylindrical vessel, may be a comparatively short tube 7^a (Figs. 5 and 6), screw-threaded at its open forward end, at 8, so as to be attached to other forms of expansion chamber bodies 7^b (Fig. 12) or 7^c (Fig. 15), the part 7^a then constituting a tubular vestibule or extension of the snow vessel of different form.

The nozzle body 4, which is employed in all of the forms, has a central bore 9 constituting an extension of the bore of the conduit tubing 3, 3^a. It is important that the supply passage throughout its length, up to the nozzle orifices, be without enlargements, or constrictions followed by enlargements, as that would tend to cause obstruction of the passage by the freezing of the refrigerant. Therefore all connections of the copper tubing 3, 3^a to pieces of apparatus, or connections effected between lengths of the tubing, are made as shown at 10 in Fig. 7.

The nozzle body 4 carries at its forward end a cluster of nozzles 11, preferably though not necessarily three in number, which are set upon beveled faces of the body to direct their jets divergently with respect to each other and obliquely toward the encircling wall of the tube 7 or 7^a. Branch channels 9^a of smaller diameter than the bore 9, so that expansion will not occur in these branches behind the nozzle orifices, are drilled obliquely radially in the body to intersect the blind forward end of the bore 9, and an enlarged outer recess is counterbored coaxially with

each of these branches, and is threaded internally to receive a screw bushing 11. Each of these bushings confines a thin disc 12 at the bottom of the recess, between gaskets 13. 5 The discs 12 are thus held across the passages 9^a, abruptly reducing the cross-section of the passageway to the minute area of fine central orifices 14 in the discs. These discs are exceedingly important, if not essential, 10 for the successful formation of the snow or frozen refrigerant by simply expanding the gas or liquid through an orifice into a chamber. The fluid emerging freely from the orifice of one of the discs is converted in large 15 part into the snowy state, and rapidly builds up a mass of the frozen material in the chamber.

With a group of nozzles of this character and general arrangement, a very effective refrigerating action is secured. The combined 20 orifices give adequate capacity and make possible great economy in the consumption of the refrigerant; and if one or even two of the nozzles should become frozen up, the remainder 25 will continue in action. The expansion of the jets occurs first in the bores of the individual bushings 11, and then in the interior of the common enclosure 7 or 7^a. In this interior there quickly forms a plug of the snowy-like 30 frozen refrigerant, which eventually fills practically the whole open interior of the vessel 7, 7^b or 7^c.

It is desirable that the perforated nozzle discs 12 be made of material having little affinity 35 for the frozen refrigerant, so that their holes will not readily become closed. Monel metal is advantageous for this reason. In the case of a metal disc the hole can be drilled with a very fine drill, and the disc may then 40 be hammered to contract the hole to an even smaller size. Materials other than metal may also be used for the discs. With glass very fine orifices can easily be produced.

A restricted outlet 15 is provided from the 45 expansion chamber, which outlet it is advantageous to place near the inlet nozzle, rather than at a remote part of the chamber. Accordingly, the fitting 15 is screwed into an opening in the side of the tubular part 7 or 7^a 50 adjacent the end of the nozzle. A coupling 16 connects the end of a flexible copper tube 17 with said fitting, and a disc 18 perforated with a small hole is held between gaskets at this point to reduce the outlet to the desired 55 fineness.

The outlet or exhaust from the expansion chamber of the snow vessel is connected by the tubing 17 with the inlet 19 of the regulator 5.

60 Said regulator is shown as provided with a body preferably formed of three sections 20, 21 and 22 screwed together. The lower section 20 having the inlet 19 is shown as having the form of an upright cylinder, the 65 chamber of which accommodates the lower

part of a spindle 24, and a spring 25 which is held under compression between a nut 26 on the lower end of the spindle and a shoulder 27 formed by the lower end of the intermediate body section, the spring consequently 70 exerting pressure downward on the spindle and members carried thereby.

One of these members is a valve 28 which is fixed to the spindle and seats upon an annular seat 29 formed in the lower part of the 75 body section 21. This valve member has a cylindrical periphery 30 of moderate depth, which has a piston fit in a low cylindrical inner wall 31 of the body section 21. Above this short piston bore, the interior of the 80 upper chamber 32 enlarges so that when the piston valve is raised above the piston bore the pressure beneath the valve is free to pass into the upper chamber. Ribs 33 beneath the valve, guide the same truly in a bore 34. 85

From the chamber 32 there is a further exhaust outlet 35, which is continued by means of copper tubing 36 to a regulator 37. The two regulators function cooperatively. The exhaust from the chamber 32 of the primary 90 regulator is a free exhaust, except when the supplementary regulator 37 acts to close it entirely in the manner which will presently be described.

The upper portion 38 of the spindle, which 95 is preferably of smaller diameter than the lower part, slides as a piston through a packing gasket 39 and in a bore 40 formed in the top body section 22. A transverse bore 41 in this section intersects the bore 40 at right angles, and constitutes a part of the supply 100 conduit 3, 3^a. The bore 41 is of the same area as the bore of the copper tubing, and the tubing is connected to the arms 42 of the regulator section 22 by coupling connections 43 105 designed to create no constriction, as heretofore explained.

The piston valve 38 is formed with an annular port 44 adapted to register with the cross bore 41 in the lowermost position of the 110 spindle 24, which is determined by the seating of the valve 28. The upper portion of the bore 40 constitutes a lubricant chamber 45 which is filled with glycerine, a screw plug 46 enabling the lubricant to be replenished. 115

Another escape from the upper exhaust chamber 32 of the regulator is marked 47. This exit is formed with a chamber which is packed with a collection of hard discs 48, which are perforated with fine holes, alternately at the center and toward the periphery, so that a difficult and circuitous course is formed through which the gas can leak only very slowly. 120

It is advantageous to include in the regulator another valve 49 which seats downwardly, that is to say toward the entrance to the regulator, against an annular seat 50 in the section 21 of the regulator body, above or beyond the valve 47. This valve has a sliding 125

piston fit on the reduced portion 38 of the spindle, which fit may be further made gas-tight by the lubricant, and is held to its seat by an independent spring 51. The function 5 of this valve when employed is to act as a non-return valve to prevent any superior back-pressure occurring at any time from interfering with the functioning of the valve 28. The pressure of the exhaust gas from the snow 10 vessel after raising the valve 28, which is comparatively heavily loaded by the spring 25, will have no difficulty in lifting the valve 49 against its light spring.

Flexible copper tubing 52 is shown leading 15 from the slow escape 47, for a purpose which will be later described.

While the primary regulator 5 is responsive to exhaust pressure, the supplementary regulator 37 is a thermal device. Preferably 20 and specifically it is a device in which the cold produced by the refrigerating system is caused to freeze water so as to form an ice-plug closing the further exhaust, while a rise in the temperature will result in the melting 25 of the barrier, so that said exhaust is again free. Consequently, the regulator 37 is mounted in a position where the cold due to the system will ordinarily be below the freezing point of water, or such other liquid or mixture as may be employed in place of water. 30 In Fig. 1 the regulator 37 is shown mounted adjustably by means of a clip 53 on a bar 54 projecting laterally from the freezing unit 55 of a refrigerator, within the refrigerator 35 enclosure, which is indicated at 56.

The said freezing unit comprises a brine box, containing brine 57, and having a recess occupied by ice-drawers 58. The expansion chamber or snow vessel 7 is set into the brine 40 box to chill the brine, and the exhaust tubing is carried in numerous turns through the brine and about the ice-drawers before being conducted outside, in order that the cold of the exhaust gas may also be imparted to the 45 brine.

The conduit 52 heretofore referred to as leading from the slow escape of the regulator 20 is carried through the brine chamber so that its open end delivers into the recess containing the drawers 58, in order that the water 50 to be frozen in these drawers may be somewhat carbonated. The carbon dioxide escaping into the atmosphere of the refrigerator is likewise an advantage in that it has a preservative action.

The regulator 37 includes a U-tube conduit 59, forming the terminal of the exhaust conduit 36, which is coupled to the upper end of the limb 60 of the U at 61. The limb 62 60 passes upward into a water reservoir 63; the upper end of this limb is closed or guarded, and the gas is permitted to escape laterally in the upper part of the reservoir, above the water body 6, through openings 64. A per- 65 forated plate 65 may be provided across the

reservoir above the body of water and below the openings 64, to keep the water from being expelled from the reservoir as the result of agitation by the outflowing gas.

The limb 60 is surrounded by a water chamber 66, which is connected with an opening in the bottom of the reservoir 63 by members 67, 68. The part 68 contains a check-valve 69, which permits liquid to pass readily from the reservoir 63 to the chamber 66, but closes 75 automatically against any pressure or flow in the reverse direction. The gas passage of the limb 60 contains a tapered constriction at 70, and immediately above this constriction inclined holes 71 are drilled through the wall 80 of the conduit in an inward and downward direction. These holes permit water to enter the exhaust gas conduit from the chamber 66, which water, as long as the conduit remains open, is carried around by the gas through 85 the U-tube, and delivered through the holes 64, to return to the body of water in the reservoir.

The part of this regulator comprising the reservoir 63, the limb 62 and the bottom of the 90 the U-tube is protected by heat (or cold) insulation 72; while the part containing the limb 60 and the water chamber 66 is un-insulated.

The operation of the foregoing parts will 95 now be briefly described.

The refrigerant, on first being turned on at the tank, flows through the tube 3, the cross-bore 41 of the regulator 5, the piston 38 then being in the lowest position in which the port groove 44 registers with the said bore, 100 through the tube 3^a to the nozzle of the expansion chamber 7. Here the expanding and evaporating refrigerant produces the intense cold, and the chamber becomes more or less filled with the carbon-dioxide snow. As the 105 snow forms in the vessel the flow of refrigerant is reduced, the expansion chamber being thus partially self-regulating. The exhaust gas passing out through the disc 18 and the line 17 enters the chamber 23 of the regulator 5, and its pressure lifts the valve 28 110 against the resistance of the spring 25. This momentarily cuts off the supply of refrigerant, because of the piston valve being raised so that its port 44 is carried out of communication with the conduit bore 41. When the piston surface of the valve 28 clears the co-operating piston bore, however, the pressure beneath the valve 28 is quickly vented past the cover valve 49, through the line 36 and 115 the regulator 37, to atmosphere. This permits the valve 28, and with it the spindle 24, and the piston valve 38 to fall, reopening the supply conduit by reason of the port 44 again registering with the passage 41. This action 120 is continually repeated while the frozen refrigerant builds up in the snow vessel and the temperature of the interior of the refrigerator or other space is being lowered to the desired degree. The action during the period 125

130

of activity is a pulsating or intermittent one, which I find to be advantageous for economy and efficiency of operation.

When a desired or predetermined degree of cold has been attained, the water or other liquid, which has been entering the limb 60 of the regulator 37 and has been carried along by the current of gas and out through the delivery orifices of the terminal limb 62 of the 5 exhaust, freezes in the tapered constriction 70, forming an ice-plug *c*, which completely blocks the gas passageway of this exhaust. Thereafter the only escape for the exhaust gas is through the very slow leak provided 10 by the collection of discs 48. This leak is substantially constant, since the greater the pressure seeking escape the more strongly the discs are pressed together and consequently 15 the more difficult is it for the gas to penetrate between their faces.

The practically complete closing of the exhaust would produce a back-pressure through the system which would in itself tend to stop the supply of refrigerant from the source 20 to the expansion chamber. It is desirable, however, to positively cut off the supply, which is accomplished by the rise of the piston valve 38. This member no longer rises and falls in such manner as to alternately 25 cut off and reopen the supply, but is kept raised by the pressure beneath the valve 28. This pressure, since it can no longer be freely vented through the exhaust 36 and the regulator 37, leaks only very gradually past the 30 valves 28 and 49 and through the slow escape 35 47, so that the valve 28, the spindle 24 and the piston valve 38 remain virtually in a state of equilibrium, or, at least, such small oscillation as there may be will not reopen the 40 refrigerant-supply passage. During this period, the pressure in the regulator 20 is maintained by the gradual melting and evaporation of frozen refrigerant in the expansion chamber.

When the carbon dioxide snow has largely melted, or when the temperature in the refrigerator or other space has risen for any other reason above a predetermined point, the ice-plug *c* melts, there is again a comparatively free discharge of exhaust pressure from the system; and the parts of the regulator 5 fall and rise, repeatedly opening and interrupting the supply of refrigerant to the nozzle of the expansion chamber, so that the 55 frozen mass is again built up and the temperature brought down.

In Fig. 12 a form of snow-vessel expansion-chamber is shown which comprises two heavy-walled metal sections 73, 74 clamped together 60 by bolts 75 through their flanges, against an interposed packing 76. The massive unit encloses a shallow cylindrical chamber, which is packed with a stack of large metal discs 77, having large central openings 78, which register with the interior of the cylindrical cas-

ing 7^a containing the multiple nozzle which has been described. The frozen refrigerant fills the central cavity and forces its way between the discs or plates. Refrigerating units of this kind are suitable for use in refrigerator cars and elsewhere. The other parts of the system are like those which have already been described.

Fig. 14 illustrates a form of system embodying the invention designed for cooling 75 the interior of a theatre, church or other building, or a cold-storage interior.

A battery of carbon-dioxide tanks 2 are connected with a manifold 80, which is connected with the supply line 3, 3^a, through the 80 regulator 5, which has been described. The line 3^a is connected with the nozzle of an expansion chamber 7, like the vessel bearing the same reference numeral which has already been described except that it may be 85 larger and longer in proportion. This vessel is inside a brine vessel 81. The exhaust line 17 from the chamber 7 may be led to the nozzle of another expansion chamber 7' in a second brine chamber 81'. From such second 90 expansion chamber an exhaust line 17' leads to the regulator 5, this regulator being connected with the supplementary regulator 37 placed in a proper location, the regulators acting in the manner which has been set forth. 95

The interiors of the brine chambers are connected at 82, and piping 83 connects them with chilling radiators 84. A pump 85 circulates the brine through the brine chambers in contact with the snow vessels and through the radiators. This apparatus is contained in a cold box or room 86, from which cold air is pumped by a blower 87 through suitable ducts and outlets to various parts of the building.

The exhaust line 17' is conducted about the gas tanks 2 for the purpose of cooling them, as the system operates most advantageously when the contents of the supply tank are kept at a temperature of about 68° 110 F. For simplicity this is indicated in the drawing by showing a single turn of the piping about the battery of tanks, but it will be understood that in practice the piping will be extended in a sufficient number of coils 115 immediately adjacent or in contact with the tanks.

In Fig. 15, the expansion chambers 7^c are themselves in the form of refrigerating radiators. A nozzle cylinder 7^a is applied to 120 one end of one longitudinal tube of each radiator, and these ends of the expansion chambers or radiators are connected in series with each other and with the gas tanks 2 by the lines 3^a, 17, 17'. From the last cylinder 7^a, 125 an exhaust line 17² passes to the regulator 5. It is desirable to also connect the far ends of the several radiator expansion chambers with this exhaust line by exhaust branches 90, containing non-return valves 91 which 130

open to pressure or flow from the radiators, but close against pressure acting in the reverse direction.

Numerous other forms, embodiments and applications of the invention will suggest themselves. While carbon dioxide is a readily available and economical liquefied refrigerant, having the desired properties, the invention is not necessarily limited to this gas, and others may be employed. The preferred mode of operation has been described in detail so that the illustrated forms of the invention may be readily understood, but it should be understood that the operation as well as the various matters of construction may be modified without departing from features of essential novelty.

What I claim as new is:

1. Means for producing cold by means of a liquefied gas, comprising a liquefied gas snow vessel, a nozzle communicating with said vessel and having connection with a source of the liquefied gas, an exhaust connected with the vessel, a regulator connected with said exhaust and controlling the supply to said nozzle, an exhaust leading from said regulator, and means subject to the cold emanating from said vessel for automatically stopping the latter exhaust with an ice plug.

2. In a system for refrigerating by means of liquefied gas, the combination with a vessel into which the refrigerant is expanded to form snow, a supply passage, and an exhaust passage, of valve means controlling the supply passage, a primary regulator connected with the exhaust passage and acted upon by the exhaust pressure to control said valve means, and a supplementary regulator responsive to thermal conditions and operative to close the exhaust passage at a point beyond the primary regulator.

3. In an apparatus for producing cold by means of a liquefied gas, the combination of a liquefied gas snow vessel having a nozzle, a supply passage connected with said nozzle, a piston valve to open and close said passage, an exhaust connected with said vessel, and a regulator connected with said exhaust having a piston relief valve operatively connected with the aforesaid piston valve.

4. In an apparatus for producing cold by means of a liquefied gas, the combination with a liquefied gas snow vessel having a nozzle and an exhaust, and a supply passage connected with said nozzle, of a regulator connected with said exhaust having a spring-loaded piston valve member above the inlet from said exhaust, a valve in the supply passage actuated by said member, a further exhaust passage leading from the regulator above said piston relief valve member, and means for automatically stopping the latter exhaust passage by an ice plug.

5. In an apparatus for producing cold by

means of a liquefied gas, the combination with a liquefied gas snow vessel having a nozzle and an exhaust, and a supply passage connected with said nozzle, of a regulator connected with said exhaust, a spring-loaded piston relief valve member in said regulator above the inlet from said exhaust, a further exhaust leading from a point above said member, a slow escape also connected with the space above said member, means for automatically stopping the passage of said further exhaust by an ice plug, and a valve operatively connected with said member and controlling the supply of refrigerant to the nozzle of the snow vessel.

6. In a carbon-dioxide or like refrigerating system, a regulator comprising a chamber having an inlet from the exhaust of a liquefied gas snow vessel, a spring-loaded piston relief valve member normally closing the chamber above said inlet, a chamber above said member, an outlet from such upper chamber, an upper body containing a liquefied gas supply passage for the snow vessel, and a piston bore intersecting said supply passage, and a friction valve operatively connected with said piston relief valve member and working in said bore, the upper part of said bore being a lubricant reservoir containing a lubricant such as glycerine.

7. In a carbon-dioxide or like refrigerating system, a regulator connected with the exhaust of a liquefied gas snow vessel, said regulator having a spring-loaded piston relief valve member, a further exhaust passage opening from the regulator at the outer side of said valve member, means for automatically stopping the latter exhaust passage by an ice plug, a liquefied gas supply passage for said snow vessel, and a valve operatively connected with said piston relief valve member adapted for cutting off and reopening said supply passage.

8. In a carbon-dioxide or like refrigerating system, a liquefied gas snow chamber having a nozzle, an exhaust from said chamber, a regulator connected with said exhaust, said regulator having a spring-loaded piston relief valve member, a further exhaust passage leading from the chamber of the regulator at the outer side of said piston relief valve member, means for automatically stopping the latter exhaust passage by an ice plug, a slow escape also opening from the said chamber of the regulator, a liquefied gas supply passage connected with the nozzle of said snow chamber, and a valve operatively connected with said piston relief valve member and adapted for closing and reopening said supply passage.

9. In a carbon dioxide or like refrigerating system, a liquefied gas snow chamber having a nozzle, an exhaust from said chamber, a liquefied gas supply passage connected with said nozzle, a regulator connected with said

- exhaust and having a spring-loaded relief valve member, a valve operatively connected with said relief valve member and controlling said supply passage, a further exhaust connected with the chamber of the regulator at the opposite side of said relief valve member, and a cover valve in said chamber seating between said relief valve member and said further exhaust.
- 10 10. In a carbon dioxide or like refrigerating system, the combination with a liquefied gas snow vessel having a nozzle, an exhaust
- from said vessel, and a liquefied gas supply passage connected with said nozzle, of a regulator connected with said exhaust, said regulator having a spring-resisting member adapted to yield to the exhaust pressure and eventually to vent the same, a valve connected with said member and controlling said supply passage, a further exhaust leading from the regulator at the outer side of said member, and means for automatically stopping said further exhaust by an ice plug.

PETER J. MUENCHEN.
